BELT TYPE BULLET HOLDER

Thomas G. Burke, 6231 182nd St. SW.,
Lynnwood, Wash. 98036

Filed Nov. 27, 1974, Ser. No. 527,565

Term of patent 14 years

Int. Cl. D3—02

U.S. Cl. D22—14

FIG. 1

FIG. 2

FIG. 1 is a front perspective view of a belt type bullet holder, with the flap open showing the interior pockets embodying my new design.

FIG. 2 is a rear perspective view as viewed with the flap closed.

I claim:

The ornamental design for a belt type bullet holder, substantially as shown.
